(57) CLAIM

The ornamental design for a lighter as shown and described.

DESCRIPTION

The patent or application file contains at least one drawing executed in colors. Copies of this patent or application publication with color drawings will be provided by the Office upon request and payment of the necessary fee.

FIG. 1 is a perspective view of an ornamental design for a lighter according to the present invention;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines illustrate portions of the lighter and form no part of the claimed design.
